TOLUENE SULFONIC ACID TREATMENT OF
AROMATIC HYDROCARBONSRalph L. Dockendorff, Goose Creek, Tex., assign-
or to Standard Oil Development Company, a
corporation of Delaware

Application April 19, 1946, Serial No. 663,417

9 Claims. (Cl. 260—674)

1

The present invention is directed to a method for treating normally liquid aromatic hydrocarbon.

In the production of an aromatic hydrocarbon it is desirable to subject the aromatic material to a finishing treatment capable of removing contaminating materials therefrom whereby a product capable of passing conventional tests is obtained without the loss of undue amounts of aromatic material. As an example of such an unfinished aromatic fraction may be mentioned the raw toluene stream commercially obtained from the treatment of petroleum fractions and comprising contaminants such as olefin and diolefin of the order of 3% and aromatic hydrocarbon of the order of 97%. It is desirable to treat such a feed stock comprising a major portion of aromatic hydrocarbon and a minor portion of contaminating material so that it will have a desirably low bromine number and will have a suitable acid wash color.

The acid wash color test is described in the U. S. Army Toluene Specification 50-11-38D dated February 12, 1943, a low acid wash color indicating the toluene to be of nitration grade.

The bromine number test is a measure of the olefin content of a hydrocarbon fraction and a description of this test method may be found in U. O. P. Laboratory Test Methods for Petroleum and its Products, page 186, published by Universal Oil Products Co., Chicago, Illinois, 1937.

A toluene having an acid wash color test of 0-1 is considered satisfactory for nitration and is of proper storage stability; the bromine number should be correspondingly low for the toluene to be used for this purpose.

In accordance with the present invention an aromatic hydrocarbon stream containing a minor portion of contaminants is brought into contact with toluene sulfonic acid in a liquid phase at a temperature of approximately atmospheric or slightly above atmospheric in order to remove the contaminants such as olefins, diolefins and the like and to obtain a treated aromatic fraction having a satisfactory bromine number and satisfactory acid wash color test.

As stated heretofore, the aromatic fraction is treated in the liquid phase with toluene sulfonic acid. The treatment may be carried out at a temperature within the range of 50° to 150° F. Usually it will be found desirable to employ a temperature of approximately 85° F. for the treatment.

The volume of toluene sulfonic acid contacted with the unfinished aromatic feed stock may be

2

varied over a substantial range and satisfactory results obtained. For example, one part of the feed stock may be intimately contacted with toluene sulfonic acid in an amount within the range of .2 to 10 parts of the toluene sulfonic acid. Similarly, the time of contact between the toluene sulfonic acid and the feed stock may be varied over a considerable range; it will be found that good results may be obtained with the time of contact within the range of five minutes to several hours. It will usually be found preferable, however, to contact the aromatic fraction with approximately an equal volume of toluene sulfonic acid and to maintain the materials intimately admixed for a time interval within the range of ten minutes to one hour.

The present invention will now be described in greater detail in conjunction with the drawing in which the sole figure is in the form of a diagrammatic flow sheet.

Turning now specifically to the drawing, a raw toluene feed stock consisting of approximately 97% toluene and approximately 3% contaminant, such as olefin and diolefin, is introduced through inlet line 11 and admixed with toluene sulfonic acid flowing through line 12. The source of the toluene sulfonic acid in line 12 will be apparent as the description proceeds. The mixture of raw toluene and toluene sulfonic acid is discharged into vessel 13 which is commonly designated in the art as a time tank and arranged to allow a sufficient time of contact between the feed stock and toluene sulfonic acid to allow the contaminants to react. From the time tank the product of the reaction is withdrawn through outlet line 14 which in turn discharges into settling vessel 15.

In the settling vessel a lighter layer comprising toluene, polymer and toluene sulfonic acid separates from a heavier layer comprising toluene sulfonic acid and toluene. The lighter layer comprises approximately equal parts of toluene and polymer and is withdrawn through outlet line 16; this fraction may be subjected to further treatment, not shown, such as distillation in order to recover toluene from the polymer. The heavy layer is withdrawn from vessel 15 through line 17 containing a heater 18 which increases the temperature of the fraction to approximately 300° F. and the heated fraction is then discharged to an evaporating vessel 19.

In vessel 19 a heavy fraction which is substantially pure toluene sulfonic acid is removed through outlet line 20 and passed through pump 21 and the stream then split with a portion pass-

ing through line 22 and returned to the stream flowing in line 17 upstream from heater 18 and another portion passing through line 23 containing cooler 24 and the cooled stream then entering line 12 where it is commingled with the raw feed stock. Make-up toluene sulfonic acid to replace that withdrawn from the system may be added through inlet 25.

The lighter, vaporous fraction removed from vessel 19 passes through outlet 26 containing cooler 27 where it is then contacted with sodium hydroxide in unit 28 in a manner well known to the art. Finished product is removed from unit 28 through outlet 29.

The practice of the present invention will be further illustrated by the following examples:

Example 1

A raw toluene fraction, obtained by the treatment of petroleum including the step of extracting with liquid sulfur dioxide a fraction having a bromine number of approximately 2.5 to 3 and an acid wash color of 1-2, was intimately contacted with an equal volume of toluene sulfonic acid at a temperature of 80-90° F. for ten minutes and was then separated from the toluene sulfonic acid by settling under the influence of gravity. The toluene fraction recovered was found to have an acid wash color of 1.

Example 2

A portion of the same raw toluene fraction used in the preceding example was admixed with an equal volume of toluene sulfonic acid and intimately contacted at a temperature of 80-90° F. for one hour and the treated toluene fraction then separated from the toluene sulfonic acid fraction by gravity settling. The toluene fraction obtained had an acid wash color of 0-1 and a bromine number of .01; the bromine number of the raw toluene was in the range of 2.5-3.0.

The acid wash color and bromine number obtained by the treatment in each of the examples given above is considered to be within the proper range to assure that the toluene samples will meet the acid wash color storage stability requirements.

It will be seen that I have described a simple effective manner for treating a feed stock comprising a major portion of aromatic hydrocarbon and contaminated with a minor portion of contaminants which allows the reduction of the contaminants to such an extent that the finished stock will satisfy the usual commercial standards for nitration grade. While I have disclosed specific examples illustrating the invention, it is to be understood that the examples are given only by way of illustration and are not intended to limit the invention in any way.

Having fully described and illustrated the practice of the present invention, what I desire to claim as new and useful and to secure by Letters Patent is:

1. A method for treating an unfinished normally liquid fraction comprising a major portion of aromatic hydrocarbon and a minor portion of unsaturated straight chain hydrocarbon contaminant including the steps of mixing said fraction in a liquid state with a sufficient quantity of substantially anhydrous toluene sulfonic

acid to form an admixture which will separate into at least two phases upon settling, settling of said admixture to separate it into two immiscible layers one of which is a toluene sulphonic acid layer, withdrawing said toluene sulphonic acid layer and distilling said withdrawn toluene sulphonic acid layer to recover therefrom a finished aromatic fraction substantially free from said contaminant.

10 2. A method in accordance with claim 1 in which the unfinished normally liquid fraction consists of approximately 97% aromatic hydrocarbon and approximately 3% contaminant.

15 3. A method in accordance with claim 1 in which the unfinished normally liquid fraction consists of approximately 97% toluene and approximately 3% contaminant.

20 4. A method for treating a raw toluene fraction, comprising the steps of mixing at a temperature no greater than 150° F. the said fraction in a liquid state with a sufficient quantity of substantially anhydrous toluene sulfonic acid to cause phase separation upon settling to improve the acid wash color of the toluene and subsequently settling to recover substantially purified toluene fraction from the acid layer.

25 5. A method in accordance with claim 4 in which the raw toluene is contacted with substantially an equal volume of toluene sulfonic acid.

30 6. A method for purifying a raw toluene fraction comprising polymer and unsaturated straight chain hydrocarbon contaminants including the steps of forming the raw toluene fraction into a liquid stream, admixing substantially anhydrous toluene sulfonic acid with the stream to form an admixture, subsequently separating the admixture under the influence of gravity to obtain a toluene polymer fraction and a fraction comprising a toluene sulfonic acid and toluene, separately removing the two fractions, distilling the fraction comprising toluene sulfonic acid and toluene to separate it into an overhead fraction of substantially pure toluene and a bottoms fraction comprising substantially anhydrous toluene sulfonic acid.

35 7. A method in accordance with claim 6 in which the recovered substantially anhydrous toluene sulfonic acid is admixed in sufficient quantity with the stream of raw toluene to cause 40 phase separation upon settling.

45 8. A method in accordance with claim 6 in which the toluene sulfonic acid admixed with the raw toluene stream is substantially equal to the volume of the raw toluene.

50 9. A method in accordance with claim 6 in which the toluene sulfonic acid is contacted with the raw toluene stream at a temperature in the range of 50° to 150° F.
